UNITED STATES PATENT OFFICE

2,568,097

PRINTER AND CHANGEABLE LIGHT SOURCE
THEREFORWarren L. Sullivan, Rochester, N. Y., assignor to
Paragon Revolute Corporation, Rochester,
N. Y., a corporation of New York

Application January 4, 1949, Serial No. 69,161

3 Claims. (Cl. 95—75)

1

This invention relates to printers for photosensitive sheets and to lighting means for use therein.

The conventional printer functions well in making blueprints, blue line prints, VanDyke negatives, brown prints, diazo prints and like photosensitive sheets which can be printed by light from a quartz mercury vapor lamp. However, such a printer is not versatile enough, without changes in the light source thereof, to print satisfactorily a type of photosensitive sheet known to the trade as Autopositive paper. This type of paper for satisfactory results, requires a light source in which the blue portion of the spectrum is substantially absent but the usual quartz mercury vapor lamp generates light including a considerable amount of the blue portion of the spectrum. Consequently when Autopositive paper is to be printed on a conventional printer, it has been the practice to feed a filter sheet for blue light into the printer along with Autopositive sheet and the tracing to be printed. This has been a source of annoyance and tends to slow down the work of the operator.

It has been proposed to introduce a filter for blue light between the quartz lamp and the inside surface of the glass contact cylinder. The extreme heat developed within the cylinder by the quartz lamp, has made it difficult to mount a suitable blue light filter within the contact cylinder in such a position that the filter material will not deteriorate quickly as a result of the presence of the extreme heat from the lamp.

In accordance with the main feature of the present invention it is proposed to provide a filter unit which can be quickly introduced within the contact cylinder of a conventional printer when Autopositive paper is printed and which can be easily removed when other types of photosensitive sheets are to be printed.

In accordance with another feature of this invention there is provided a combined filter and light unit which can be readily inserted within the contact cylinder of the printer for use instead of the quartz lamp when Autopositive paper is to be printed.

According to another feature of the invention, there is provided a replaceable unit or frame having mounted therein a plurality of green fluorescent lamps each enclosed by a suitable yellow material to filter out any blue light.

Other features and advantages of the invention will appear from the detailed description and claims when taken with the drawings in which:

Fig. 1 is a side elevation of a printer for photo-

2

sensitive paper and the like, said printer having the present invention incorporated therein;

Fig. 2 is a sectional view taken substantially on the line 2—2 of Fig. 1;

Fig. 3 is a front elevation of a unit comprising a multiple light source with a filter which can be removably supported in the printer;

Fig. 4 is an end view of the unit of Fig. 3;

Fig. 5 is a section taken substantially on the line 5—5 of Fig. 4 looking in the direction of the arrows and showing particularly the mounting of one of the fluorescent tubes in the unit;

Fig. 6 is an enlarged fragmentary sectional view taken substantially on the line 6—6 of Fig. 3 showing particularly one longitudinal edge of the unit and the mounting thereon of one of the rollers which facilitate the insertion and removal of the unit from the printer;

Fig. 7 is an enlarged sectional view taken substantially on the line 7—7 of Fig. 3 looking in the direction of the arrows and showing the construction of the other longitudinal edge of the unit;

Fig. 8 is an end view of another form of the invention wherein the conventional light source of a printer can be used in combination with the modified unit of the present invention which carries a suitable filter for filtering out undesired wave lengths of light;

Fig. 9 is a front elevation of this modified unit;

Fig. 10 is a longitudinal section of this last-named unit taken substantially on the line 10—10 of Fig. 8;

Fig. 11 is a fragmentary sectional view taken on line 11—11 of Fig. 8;

Fig. 12 is a detailed sectional view of the unit taken on the line 12—12 of Fig. 9; and

Fig. 13 is a chart showing the spectral curve of a green fluorescent lamp and also showing the effect of passing this light through a yellow filter.

Referring especially to Figs. 1 and 2, there is disclosed a conventional type of printing machine which is adapted for the printing of usual blueprints and the like from tracings. This machine comprises the spaced end frames 5 and 6 having opposed openings therein through which a conventional light source L can be serviced and through which the unit of the present invention can be introduced into the machine. The end frames are supported in spaced relation in any suitable manner and are provided with bearings in which spaced pairs of rollers 7 and 8 (Figs. 1 and 2) are journaled. These rollers support a transparent contact cylinder 10, preferably made

of heat-resistant glass and open at its ends. Each edge of the glass cylinder is reinforced by a flanged ring 12 with a layer of felt 13 interposed between the adjacent margin of the cylinder and the flange thereby tending to protect the glass cylinder against breakage. The peripheries of the rings 12 ride on the pairs of rollers 7 and 8. This cylinder is adapted to rotate around the light source L located coaxially therewith.

As shown in Figs. 1 and 2 this light source is preferably a quartz mercury vapor lamp 14 which is completely enclosed by a transparent shield 15 of the type disclosed in Patent No. 2,457,353 granted to Davis, December 28, 1948, and owned by the common assignee of this application. The shield 15 is secured adjacent its ends on brackets 16, in turn attached to uprights 17 integral with end frames 5 and 6.

The glass cylinder is rotated by an endless belt 18 which engages a substantial portion of the periphery of the cylinder so that a photosensitive sheet with a tracing or the like superimposed thereon, can be held in close contact with a considerable area of the outer surface of the glass cylinder, during the printing operation. As herein illustrated, a single endless belt is used for this purpose but it will be understood that a plurality of belts arranged side-by-side and having the width of the single belt, may be used instead. The path of the belt can be traced from the left-hand side of Fig. 1 where the upper side thereof passes around a substantial part of the periphery of the cylinder and thence around the guide rolls 20, 21, 22, 23 (Fig. 1) and guide rolls 24 (Fig. 2). It will be noted that guide roll 24 is secured to the shaft on which the guide rolls 8 are mounted. A suitable driven pulley (not shown) serves to drive the belt in the direction indicated by the arrows.

It will be understood that in use, when the photosensitive sheet together with the superimposed tracing thereon are inserted at the point A in the printer, they will be engaged between the belt and the adjacent portion of the peripheral surface of the cylinder 10 and will be advanced past the light source L. The tracing and the portion of the photosensitive sheet printed therefrom will emerge from the periphery of the cylinder at the point B where both of these sheets will drop into a suitable receptacle (not shown).

The opening in each frame is surrounded by a horizontal flange 25. The inner edge of each of these flanges is lined by a strip of felt 26 or the like having one of its edges closely engaging the face of the ring 12 located at the adjacent end of the glass cylinder 10. This felt serves to reduce leakage of air between the two frames and the respective ends of the cylinder so that a cooling stream of air can be drawn through the cylinder by means (not shown), without the possibility of substantial leakage of this air at the junction between the frame and the rotating cylinder.

In the conventional printer there are provided adjustable shutters 28 and 29 respectively located at each side of the light source, which shutters serve to vary, at will, the time of exposure of the photosensitive sheet being printed, to the light passing through the glass wall of the cylinder 10. Mechanism is provided whereby these shutters can swing toward or away from each other to determine the desired aperture for light transmission. As shown in Fig. 1 the shutter 28 is secured to a shaft 30 while the other shutter 29 is secured to a shaft 31 in spaced parallel rela-

tion to the first shaft. These shafts are journaled in the brackets 16, the shaft 30 extending outward through the opening in the frame 5 where it terminates in a bevel gear 32. This bevel gear meshes with a second bevel gear 33 secured to a shaft 34 which is rotatably journaled in a part of the adjacent bracket 16. The shaft 34 terminates in a hand wheel 36 which serves to rotate shaft 34 and in turn the bevel gears 32 and 33. These gears rotate the shaft 30 which swings the shutter 28 with respect to the light source. The shaft 31 which carries the shutter 29 is provided with a gear 36 meshing with a gear 37 on the shaft 30. Consequently, when shaft 30 is rotated in one direction, the shaft 31 with its shutter 29, is rotated in the reverse direction. Thus by a single operation of the hand wheel 36 the position of the two shutters 28 and 29 can be adjusted at will to increase or restrict the size of the aperture.

In accordance with the present invention, there is provided a metal light shield 39 of a size to project through the contact cylinder and to bridge well beyond the portion thereof between the points A and B (Fig. 1). This shield has its outer surface covered with felt or the like so that it will not mar the surface of the contact cylinder if it should accidentally come into contact therewith. The shield is secured on the flanges 25 on each end frame by means of the adjusting screws 42. Apertured extensions 44 on the shield receive the respective screws 42 while a pair of lock nuts 45 threaded on each screw grip an extension therebetween. A nut 46, threaded on each screw, engages the flange 25 and provides a further adjustment whereby the shield can be spaced with great accuracy from the inner surface of the contact cylinder. The right hand margin of the shield (Fig. 1) provides a horizontal track portion 47, while a vertical flange 48 secured on this margin provides a related vertical track. The left hand margin of the shield has secured thereto a bracket 49 with an upturned edge, the bracket also serving as a horizontal track.

The tracks 47, 48 and 49 are adapted to guide and support an arcuate unit serving to transmit through the contact cylinder, suitable light from which the undesirable blue rays have been filtered. This unit which is at least as long as the cylinder is provided with rollers 50, 51 and 52 at its respective long edges. These rollers ride on the tracks 47, 48 and 49 and accurately guide the unit into and out of the printer as well as accurately support the unit in the proper position for use when required. Removable brackets 54, which are attached to the flanges 25 (Fig. 2), hold the unit in place.

The unit comprises the end supports 53 which are held in spaced relation by the bars 55, 56 and 57. Preferably the rollers 50 are mounted on the bar 55, while the rollers 51 and 52 (Fig. 4) are mounted on the bar 57. The supports 53 at the respective ends of the unit have insulatedly secured therein sockets 59 (Fig. 5) in which a bank of green fluorescent lamps 60 are removably fastened as herein illustrated. Each lamp 60 is covered by a layer 61 of yellow filter material whereby all blue rays from the light source are filtered out. A spectral curve C of a suitable green fluorescent lamp is shown in the chart of Fig. 13. The shaded area D of this chart shows how a yellow filter such as the layer 61, cuts off the undesired blue light.

75 The printer as illustrated in Figs. 1 and 2 is in

readiness to print Autopositive paper merely by turning on the green fluorescent lamps 60. The printer can then be operated in the well-known manner. It will be understood that during this operation the quartz mercury vapor lamp 14, is not used. When it is desired to use the printer in the conventional manner for printing blue-prints and the like, the brackets 54 are removed. The unit can then be completely withdrawn from the printer through the opening in the right side thereof (Fig. 2). The quartz mercury vapor lamp 14 is then lighted so that the printing can proceed in the usual manner.

In the modified form of the invention shown in Figs. 8 through 12 it is proposed to use a light source L including a quartz mercury vapor lamp 14 of the type now currently used in the printer but with its intensity and consequently its heat output both reduced by well known means (not shown) in its electrical energizing circuit. A unit including a yellow filter alone, is used. This unit comprises an arcuating frame made of end pieces 65, 65 spaced by the edge bars 55 and 57 as well as by the intermediate angle bars 67 (Fig. 12). These bars support in arcuate form a layer of yellow filter material 69. This unit is normally held in the printer by the brackets 54. However, when the brackets are removed the unit can be withdrawn from the printer, the rollers 50, 51 and 52 serving to facilitate this operation.

What I claim is:

1. In combination with a printer for photosensitive sheets having a rotatable transparent contact cylinder, a lighting device mounted within said cylinder, belt-like means covering a substantial portion of said cylinder whereby said sheets are brought into contact with the periphery of said cylinder to be printed therethrough, a light shield supported within the cylinder to bridge the uncovered portion thereof, spaced tracks on the margins of said shield extending parallel to the axis of said cylinder, an arcuate unit removably positioned between said lighting device and the inner surface of said cylinder, said unit including filter means for preventing rays of light in a given portion of the spectrum from passing through said cylinder, and spaced members on said unit engaging said tracks to guide said unit into and out of its position within the cylinder.

2. In combination with a printer for photosensitive sheets having a rotatable transparent contact cylinder, belt-like means covering a substantial portion of said cylinder whereby said sheets are brought into contact with the periphery of

said cylinder to be printed therethrough, a light shield supported within the cylinder to bridge the uncovered portion thereof, spaced tracks on the margins of said shield extending parallel to the axis of said cylinder, an arcuate unit removably positioned between said lighting device and the inner surface of said cylinder, said unit including a plurality of fluorescent lamps enclosed by filter material for preventing rays of light in a given portion of the spectrum from passing through said cylinder, and spaced members on said unit engaging said tracks to guide said unit into and out of position within the cylinder.

3. In combination with a printer for photosensitive sheets having a rotatable transparent contact cylinder, belt-like means covering a substantial portion of said cylinder whereby said sheets are brought into contact with the periphery of said cylinder to be printed therethrough, a light shield supported within the cylinder to bridge the uncovered portion thereof, spaced tracks on the margins of said shield extending parallel to the axis of said cylinder, an arcuate unit removably positioned between said lighting device and the inner surface of said cylinder, said unit including a plurality of green fluorescent lamps enclosed by yellow filter material for preventing rays of light in a given portion of the spectrum from passing through said cylinder, and spaced members on said unit engaging said tracks to guide said unit into and out of position within the cylinder.
